UNITED STATES PATENT OFFICE

153,888

DESIGN FOR A NUT CRACKER

John K. Martens, Hutchinson, Kans.

Application April 7, 1947, Serial No. 138,207

Term of patent 7 years

(Cl. D44—1)

To all whom it may concern:

Be it known that I, John K. Martens, a citizen of the United States, residing at Hutchinson, in the county of Reno and State of Kansas, have invented a new, original, and ornamental Design for a Nut Cracker, of which the following is a specification, reference being had to the accompanying drawing, forming part thereof.

The figure is a perspective view of a nut cracker, showing my new design.

I claim:

The ornamental design for a nut cracker, as shown.

JOHN K. MARTENS.
